Application April 1, 1946, Serial No. 658,774

5 Claims. (Cl. 74—7)

1

This invention relates to direct cranking electric starters such as are used on internal combustion engines in aircraft, and other installations. Some features of the invention, however, may be readily applied to other purposes.

An object of this invention is to provide a starter having an extremely high power to weight ratio.

Another object of this invention is to provide a starter which can not engage with the running engine, and thereby become damaged.

A further object of this invention is to provide a starter which may readily be inserted or removed from its housing, thereby permitting of easy access to all of its moving parts.

A feature of this starter is its one-piece metal housing construction which insures concentricity of its rotating parts.

Another feature of this starter is the novel construction of the friction spring which eliminates the necessity for a plurality of coil springs with a consequent saving in space and weight.

An object of this invention is to provide a brush box assembly in which any single brush or brush insulator may be removed without disturbing the others.

A feature of this invention is a quick disconnect means by which the baffle plate is joined to the mounting flange by a cam lock.

A further feature of this invention is the novel construction of the spline nut whereby the jaw is advanced into position.

A final feature of this invention is the novel oil seal provided around the jaw shaft to prevent the entry of foreign matter into the starter mechanism.

The invention consists of the construction, combination and arrangement of parts, as herein described, illustrated and claimed.

In the accompanying drawings, forming part hereof, is illustrated one form of embodiment of the invention, in which drawings similar reference characters designate corresponding parts, and in which:

Figure 1 is a sectional view of the drive mechanism of the starter with some of the parts shown in elevation.

Figure 2 is a sectional view of the starter motor with some of the parts shown in elevation.

Figure 3 is a section taken on line 3—3 of Figure 1.

Figure 4 is a sectional view of the baffle plate assembly.

Figure 5 is a side elevation of the friction spring.

2

Figure 6 is an elevation, partially cut away, of the wave spring.

Figure 7 is a longitudinal section of the screw shaft.

6 Figure 8 is a sectional view of the camlock.

Figure 9 is a section taken on line 9—9 of Figure 2.

Figure 10 is a plan view of the brush spring holder.

10 Figure 11 is a side elevation of the brush spring holder.

Figure 12 is a side elevation of a spline nut, partly cut away, in accordance with the present invention.

15 Figure 13 is a side elevation of the helically toothed gear, partially broken away, as shown in Figure 7.

Figure 14 is an end view of Figure 12, looking in the direction indicated by the arrow 14 in Figure 12.

20 Referring to the drawings, and particularly to Figure 2, 15 indicates a yoke to which a cover plate 16 is attached by screws 17. Four separate brush box insulators 18 are riveted to the cover plate 16.

25 The construction of the four brush box insulators 18 is best shown in Figure 9 in which can be seen their location on the cover plate 16. Brush boxes 19 and brush rests 20 are 30 rigidly secured to the insulator blocks 18. A terminal post 21 is located between two of the brush box insulators 18 and projects through both sides of the cover plate 16.

35 Four brush spring assemblies 22 of a construction best shown in Figures 2, 10 and 11, are inserted in rectangular openings 23 in the yoke 15. Each brush spring assembly 22 comprises a holder 24, in which is carried a freely slideable cup member 25 into which the coil spring 26 is 40 inserted. The closed end of the cup member 25 presses against the top of the brush and the coil spring 26 forces the said brush against the commutator 27. Rearward motion of the coil spring 26 is prevented by an insulating washer 28 45 pressed into the open end of the holder 24. The dielectric holder 24 is provided with shoulders 29 so constructed that once the spring assembly has been inserted in the rectangular yoke opening 23 a slight rotation of its position causes the shoulders 29 to seat themselves upon the inside of the yoke 15. This construction provides a means for readily inserting or removing any brush without disturbing the others.

50 The yoke's four larger rectangular openings 23 provide easy access to the brushes over which

they are located. A spring steel band 30 is snapped over the yoke 15 to cover the openings 23 and is secured by means of tie wires.

The cover plate 16 (Figure 2) is centrally bored 31 to receive a ball bearing 32 upon which the commutator end 27 of the armature 33 is supported. A nut 34 attached to a hub 35 on the plate 16 holds the bearing 32 in place. The armature 33 is secured to the central shaft 39 by means of a screw 40 locked to it.

Four field coils 36 connected in series-parallel are held to the pole shoes 37 which are secured to the yoke 15 by means of flat head screws. Two terminals soldered to the ends of the coils are connected, one to the inner extension of the terminal post 21 and the other to a positive brush box 38.

The forward end of the armature shaft 39 (shown in Figure 1) is hollowed and internally threaded to receive the starter driving pinion 41. The threads on the pinion 41 cause it to be tightened to the starter shaft 39 as a result of the torque transmitted during the starter's operation. The pinion 41 also retains a ball bearing 42 to the shaft 39. The outer race of the ball bearing 42 is held by a steel plate 43 attached to the inside of the yoke 15. This plate 43 divides the motor assembly of the starter from the drive section.

The drive section is actuated by the gear teeth 44 of the pinion 41 which engage with two first stage planet gears 45. A first stage spider 46 carries the two first stage planet gears 45 on ball bearings 47. The gears 45 mesh with a stationary internal gear 48. This internal gear 48 is machined into the bore of the steel shell 49 of the starter.

The first stage spider 46 has a sun pinion 50 integral therewith and the whole rotates upon a bronze shaft 51 which maintains the spider 46 in axial alignment.

The sun pinion 50 engages with two second stage planet gears 52 which are mounted upon roller bearings 53 on a second stage spider 54. The second stage planet gears 52 also mesh with the internal gear 48 of the shell 49. This spider 54 also has its sun pinion 55 which rides upon the bronze shaft 51.

The second stage sun pinion 55 drives the four planet gears 56 which are mounted on needle bearings 57 fixed to hardened studs on the starter barrel 58.

The spiders 46, 54 rotate freely on the shaft 51 but are held in position by washers 59, 60 and a lock ring 61 snapped in a groove at the end of the shaft 51. A nut 62 holds the shaft 51 to the barrel 58 and increases its axial stability. Lock washers 63 are provided to maintain the nut 62 in place.

The gear train comprising the series of planetary sun and fixed gears imparts its torque to the barrel 58 which rotates within a bore 64 of the starter shell 49. The barrel 58 is provided with a collar 65 spaced from its forward end which bears against the forward end of the shell 49 and prevents rearward movement of the starter mechanism. The barrel bore is splined at 66 to receive a plurality of external clutch discs 67. These discs 67 are made of steel faced with a special powdered bronze material. A plurality of inner clutch discs 68 are supported within the outer discs 67 and are splined to the spline nut 69 best shown in Figure 12.

A wave type spring 70, shown in detail in Figure 6, compresses the clutch discs 67, 68 (Fig-

ure 1) between a clutch plate 71 and a clutch backing plate 72, thereby transmitting the barrel torque to the spline nut 69. A clutch adjusting nut 73 threaded into an enlarged bore of the barrel 58 permits of clutch adjustment by varying the pressure on the wave type spring 70 upon which it bears.

The spline nut 69, driven by the clutch discs 67, 68, is prevented from moving laterally by 10 means of a lock ring 74 snapped into a groove machined in the rearward end of the said nut 69. An internal shoulder 75 is provided, spaced from the front of the spline nut 69, and the entire bore of the nut 69 threaded with a coarse 15 left hand thread 76.

A screw shaft 77, shown in detail in Figure 7, is threaded within the spline nut 69 by means of a gear 78, shown in Figure 13, having helical teeth machined into a collar 79 on the rearward end of the said shaft 77. The forward end of the screw shaft 77 is provided with a collar 80 into which is cut a gear 81 having straight teeth.

The screw shaft 77 is bored from each end as shown in Figure 7. A pierced wall 82 integral 25 with the shaft 77 is provided in the shaft bore intermediate the ends of the said shaft 77. A coupling shaft 83 is held within the bore 84 of the wall 82. A coil spring 85 slipped over the shaft 83 bears against the forward face of the wall 82. 30 A lock ring 86 snapped into a groove 87 on each end of the coupling shaft 83 enables the shaft 83 to join the screw shaft 77 and the starter jaw 88.

As shown in Figure 1, the forward end of the 35 coil spring 85 bears against a third lock ring 86 on the shaft 77. This ring 86 holds a metal washer 89 against a rubber ring 90, surrounding the coupling shaft 83, and flush with the back of the starter jaw 88. This rubber ring 90 prevents oil or foreign matter from entering the 40 starter at this point. Protection is further insured because the shaft 83 does not move through the jaw 88 as is the case in presently known starters.

The starter jaw 88 is provided with an internal gear 91 which meshes with the gear 81 on the forward end of the screw shaft 77. The torque imparted to the screw shaft 77 by the gear train is thereby transmitted to the starter jaw.

50 A friction spring 92, shown in detail in Figure 5, is slipped over the outside diameter of the starter jaw 88. The spring 92 is formed of two turns of square wire wound so that its inside diameter is smaller than the outside diameter of the jaw 88 over which it is sprung. One end 55 of the spring 92 is bent at right angles to its vertical axis to form a projecting member. As shown in Figure 4, this bent end 93 is held within a detent 94 formed in the baffle plate assembly.

55 In this manner the spring 92 is prevented from rotating with the starter jaw 88 which it encircles. The cranking rotation of the starter jaw 88 within the spring tends to free the spring 92 from the jaw 88 by increasing the inside diameter of the spring 92. The normal spring 60 friction upon the jaw 88 prevents it from moving forward for any reason other than the operation of the starter. This prevents the jaw teeth 96 from engaging the running engine and thereby becoming damaged. The spring friction also 65 serves a purpose hereinafter described.

The front end of the starter is covered by the 70 baffle plate assembly 95. This also serves to pilot the starter to the engine mounting flange (not shown). The baffle assembly comprises a

baffle plate 97 to the inside of which are attached, as by welding, two stamped steel plates 98, 99. The first 98 of these is in the shape of a large washer encircling the starter jaw 88 and retaining upon its inner face the friction spring 92. The second, or jaw support plate 99 has a rearwardly extending rim 100 which forms a bearing surface within which the starter jaw may rotate and which restricts the radial movement of the jaw 88 under engine vibration.

The jaw support plate 99 is also provided with a recess 101 to accommodate the friction spring 92 and a detent 94 to hold the bent end 93 of the said spring. A spring loaded oil seal 102 is pressed into and secured between the starter jaw 88 and the baffle plate 97 to prevent the entry of engine oil or foreign matter into the starter.

To facilitate the disassembly of the starter, camlocks 105 are provided to couple the baffle plate 97 to the starter mounting flange 103. A spacer flange 104 is inserted between the baffle plate 97 and the mounting flange 103 to provide flange strength. In removing the starter from the engine mounting flange, the baffle plate 97 often becomes frozen to the engine flange. This necessitates much prying and consequent injury to the baffle plate 97 before it can be removed. By holding the baffle plate 97 to the starter mounting flange 103 by means of the camlocks 105, shown in Figure 8, this difficulty is avoided and the problem of removing the starter greatly simplified. A quarter turn of the camlock 105 frees the baffle plate 97 from the mounting flange 103 and permits of access to the inside of the starter.

The operation of the starter becomes apparent from the foregoing description. The torque provided by the starter motor is transmitted by means of the motor shaft 39 and the driving pinion 41 to a series of planetary gears 45, 52, 56, forming part of a gear train. The effect of this mechanism is to greatly increase the torque available at the starter barrel 58. The rotary motion of the barrel 58 is transferred to the spline nut 69 by means of a clutch mechanism adjustably regulated by the tension placed upon a wave spring 70 by the clutch nut 73. The motion of the spline nut 69 would cause the screw shaft 77 to rotate but for the operation of the friction spring 92. The friction spring resists this torque by holding the starter jaw 88 to which the screw shaft 77 is geared. However, this causes the left hand splines 76 within the spline nut 69 to force the screw shaft 77 forward. The starter jaw 88 is yieldably urged forward by the coil spring 85 surrounding the coupling shaft 23 which links the screw shaft 77 and the jaw 88. The forward travel of the screw shaft 77 and jaw 88 is stopped by the shoulder 75 in the spline nut 69, whereupon the entire barrel assembly, including the clutch jaw 88 rotates, thereby cranking the engine. When the screw shaft 77 reaches the end of its travel the rotation of the jaw 88 expands the friction spring 92 and frees the jaw 88 for rotation.

When the motor is at rest, the screw shaft 77, as well as the starter jaw 88 splined to it must rotate in the direction opposite to the cranking direction in order for these parts to move forward. This opposite direction of rotation, however, causes the friction spring 92 to become more tightly wound around the outside diameter of the jaw 88. Thus the jaw 88 is held from moving, under engine vibration or airplane maneuver-

vers, into a position of contacting the running engine which would cause serious injury to the starter and its jaw 88.

The jaw 88 of the starter is provided with inclined teeth so that the starting of the engine under its own power and its consequent crank-shaft speed in excess of the starter speed causes the starter jaw 88 to be thrown clear of driving engagement and possible damage.

10. The starter shell 49 is attached, as by welding, to the yoke 15 of the motor section. The two are then bored and machined to the desired shape. This promotes concentricity throughout the starter and improves its performance and durability.

Having thus fully described the invention, what is claimed as new and desired to be secured by Letters Patent of the United States, is:

1. In an engine starter, a source of rotary power, a reduction gear train driven by said power source, a barrel driven by the gear train, a clutch mechanism coupled to the barrel, a spline nut driven by the clutch, a screw shaft rotatably carried within the said spline nut and driven thereby, a jaw member slidably carried upon the screw shaft and driven by the screw shaft, a baffle plate having a jaw receiving opening therein upon the front of the starter, a coil spring carried upon the jaw member, said spring having an outwardly disposed detent thereon secured to the baffle plate and an internal diameter slightly smaller than the outside diameter of the jaw member, said spring being adapted to permit the jaw to rotate in only one direction.

2. In an engine starter, a source of rotary power, a reduction gear train comprising a stationary internally geared housing and a plurality of planetary gears in mesh with the internal gear, driven by said power source, a barrel driven by the gear train, a clutch mechanism coupled to the barrel, a spline nut driven by the clutch, a screw shaft rotatably carried within the said spline nut and driven thereby, a jaw member slidably carried upon the screw shaft and driven by the screw shaft, a baffle plate having a jaw receiving opening therein upon the front of the starter, a coil spring carried upon the jaw member, said spring having an outwardly disposed detent thereon secured to the baffle plate and an internal diameter slightly smaller than the outside diameter of the jaw member, said spring being adapted to permit the jaw to rotate in only one direction.

3. In an engine starter, a source of rotary power, a reduction gear train comprising a unitary stationary, internally geared housing and a plurality of planetary gears in mesh with the internal gear, driven by said power source, a barrel driven by the gear train, a clutch mechanism coupled to the barrel, a spline nut driven by the clutch, a screw shaft rotatably carried within the said spline nut and driven thereby, a jaw member slidably carried upon the screw shaft and driven by the screw shaft, a baffle plate having a jaw receiving opening therein upon the front of the starter, a coil spring carried upon the jaw member, said spring having an outwardly disposed detent thereon secured to the baffle plate and an internal diameter slightly smaller than the outside diameter of the jaw member, said spring being adapted to permit the jaw to rotate in only one direction.

4. In an engine starter, a source of rotary power, a reduction gear train comprising a stationary, internally geared housing and a plurality

of planetary gears in mesh with the internal gear, driven by said power source, a barrel driven by the gear train, a clutch mechanism coupled to the barrel comprising a plurality of clutch plates, a wave spring compressing the plates and a tension nut held within the bore of the barrel, a spline nut driven by the clutch, a screw shaft rotatably carried within the said spline nut and driven thereby, a jaw member slidably carried upon the screw shaft and driven by the screw shaft, a baffle plate having a jaw receiving opening therein upon the front of the starter, a coil spring carried upon the jaw member, said spring having an outwardly disposed detent thereon secured to the baffle plate and an internal diameter slightly smaller than the outside diameter of the jaw member, said spring being adapted to permit the jaw to rotate in only one direction.

5. In an engine starter, a source of rotary power, a reduction gear train comprising a stationary, internally geared housing and a plurality of planetary gears in mesh with the internal gear, driven by said power source, a barrel driven by the gear train, a clutch mechanism coupled to the barrel comprising a plurality of clutch plates, a wave spring compressing the plates and a ten-

sion nut held within the bore of the said barrel, a spline nut driven by the clutch, a screw shaft rotatably carried within the said spline nut and driven thereby, a jaw member slidably carried upon the screw shaft and driven by the screw shaft, a baffle plate having a jaw receiving opening therein upon the front of the starter, a coil spring comprising turns of square wire carried upon the jaw member, said spring having an outwardly disposed detent thereon secured to the baffle plate and an internal diameter slightly smaller than the outside diameter of the jaw member, said spring being adapted to permit the jaw to rotate in only one direction.

ROMEO M. NARDONE.
